United States Patent Office

Des. 183,819
Patented Oct. 28, 1958

183,819

ILLUMINABLE HOUSE NUMBER SIGN

Theodore C. Von Hiltmayer and William A. Lill,
Port Huron, Mich.

Application March 18, 1957, Serial No. 45,313

Term of patent 3½ years

(Cl. D1—7)

FIG. 1

FIG. 2

FIG. 3

FIG. 4

Fig. 1 is a front elevational view of an illuminable house number sign embodying our new design;

Fig. 2 is a view taken perpendicular to the plane of the top;

Fig. 3 is a side elevational view; and

Fig. 4 is a sectional view taken on the line 4—4 of Fig. 1.

The numbering per se indicated by dot and dash lines in Fig. 1 is shown for illustrative purposes.

We claim:

The ornamental design for an illuminable house number sign, as shown and described.
